TELEVISION SYSTEM

Roscoe H. George and Howard J. Heim,
La Fayette, Ind., assignors, by mesne assignments, to Radio Corporation of America, New York, N. Y., a corporation of Delaware

Application September 2, 1931, Serial No. 560,798

14 Claims. (Cl. 178—7.5)

This invention relates to television systems, and particularly to a system in which synchronism between the transmitting and receiving stations will be maintained during time intervals substantially less than that required for the scanning of a complete picture or frame.

This invention contemplates the transmission of synchronizing signals during the time interval occurring between the completion of one pictorial element and the beginning of a succeeding pictorial element. Thus, in the case of the ordinary scanning system, where a linear pictorial element, usually along one dimension of the image, is taken, an idle time interval occurs between the end of one linear element and beginning of a new linear element. If the linear element is taken at the top of the picture from left to right, in a generally horizontal direction, the second linear element is taken below the first, and substantially parallel therewith. These linear elements are taken until the bottom of the picture is reached, when a new frame or picture is started all over again. Hence, the complete scanning operation consists of a repeated series of discontinuous cycles, each cycle representing a continuous linear pictorial element. Each series of discontinuous cycles may be considered as making up a complete frame and by repeating the series, a number of frames make up a scene.

This invention contemplates the transmission of synchronizing impulses during the periods of discontinuity of image currents. Furthermore, a special synchronizing impulse occurring during the interval between the end of one frame and the beginning of a new frame is transmitted for framing the image. Since such synchronizing impulses occur during periods of non-transmission of picture impulses, the same transmission channel may be used without the necessity for any special modulating or combining of the synchronizing and picture impulses. This results in simplicity at the transmitting system.

By making the synchronizing impulses of an amplitude substantially greater than any normal picture impulses, it is possible to effectively separate the two sets of impulses from each other at the receiving station without the use of the customary filters or other series of resonant circuits.

This invention contemplates a receiving system in which a remarkable degree of freedom from mechanical devices is obtained. In the receiving system the scanning movements of the light spot are obtained by electric means, in contradistinction to the usual mechanical means of the pres-

ent-day receivers. The synchronizing adjustment of the receiving station merely consists of one or more resistances, whose value may be simply and easily changed. A property of this receiving system is its ability to change either one of the dimensions of the image independently of the other, thus making it possible to transform ordinary scenes into grotesque or comic scenes.

A television system of the above character is characterized by its utter simplicity, particularly at the receiving end, and it is adaptable to large-scale production.

While in the system disclosed herein, scanning is effected as pointed out above, it is to be understood that any method of scanning may be used. In certain types of scanning, such as the spiral curve, it is clear that only one synchronizing impulse occurring between successive pictures would be practical.

In the receiving system herein disclosed, a feature of the invention lies in the fact that the actual scanning or movement of light spot along the image is effected by the receiving mechanism substantially independently of the transmitting mechanism, and that the assumption of a new initial position by the spot of light for repeating a previous cycle is governed by the transmitting station.

This action in the receiver is obtained by steady variation of a potential ultimately applied to the scanning means, which potential is suddenly changed in an opposite sense in value by means of a synchronizing impulse. This synchronizing impulse, which is preferably built up to a certain predetermined potential in the receiver, is applied to means which is adapted to abruptly change its electrical condition from non-conducting to conducting upon the application of this critical potential. This change of condition results in a sudden variation in value of the potential previously mentioned, and serves to synchronize the scanning means at a certain portion of its cycle with the scanning means of the transmitting system at a similar portion of its cycle.

In this particular case, a critical synchronizing potential is applied to the grid of a grid controlled gaseous discharge tube. This tube, when properly connected in the circuit, has the property of having a gaseous discharge initiated therein upon a suitable change of grid bias. Such change may be of an exceedingly minute character, so that the system is trigger-like in its action. Such a tube is shown in British Patent No. 280,870.

Referring to the drawing:

Figure 1 is a diagrammatic showing of a television transmitting system;

Figure 2 shows the relation of the synchronizing impulses to the picture impulses; and

Figure 3 shows a receiving system.

The transmitting system may be of any type whatsoever and, as shown here, comprises a motor driving the usual scanning disc with a series of apertures arranged in the form of a spiral. As the scanning disc is rotated, each aperture travels along a substantially linear element, horizontally disposed. Each succeeding element is disposed below the previous one until the bottom of the picture is scanned, when a new frame is begun with a scanning element at the top thereof. Picture impulses corresponding in intensity to the variations of light in the picture are transmitted by a photo-cell to a suitable amplifier, from there to a modulator, and thence to some transmitting system.

Arranged to rotate with the scanning disc is a synchronizing disc having a series of apertures corresponding to the scanning disc apertures. The synchronizing apertures are so related to the scanning disc apertures that a powerful source of light flashes a beam through a synchronizing aperture just during the time between the scanning of successive linear elements of the picture. This staggering of the picture and synchronizing impulses may be obtained by disposing the source of light on the photo-electric cell at a sufficiently close distance to the synchronizing disc so that as one of the synchronizing apertures, indicated by LS, flashes by, a linear synchronizing signal of exceedingly short duration is emitted by the photo-electric cell. The relative amplitudes of the impulses from both photo-electric cells are so adjusted that the amplitude of the synchronizing photo cell is substantially greater than any ordinary picture impulse. By having an exceedingly powerful source of illumination or by suitably amplifying the synchronizing impulses relatively to the scanning impulses, synchronizing impulses of greater amplitude than any normal picture impulses may be obtained. By having a one stage or any odd numbered stage amplifier between the synchronizing and picture photo cells, a phase reversal between the two types of impulses is obtained. Hence the amplitude of the synchronizing impulses represents a decrease in light intensity.

The type of wave sent out by the transmission system of Figure 1 is shown in full lines in Figure 2. The substantially square top, indicated by LI, indicates the linear synchronizing impulses, while the remaining portions of the curve are examples of picture impulses. As is clear from the curves, a certain base line is taken for absolute darkness and current impulses of greater amplitude represent synchronizing impulses and have no effect on the picture portion of the system.

In order to synchronize the complete frame at both ends—in other words, to synchronize the end of the spiral of the scanning disc with the corresponding mechanism at the receiving end—I preferably dispose a slot FS in the synchronizing disc adjacent one of the linear synchronizing apertures. Slot FS is large enough so that a light impulse of a duration substantially longer than the linear synchronizing impulses is flashed to the photo cell. Obviously, the framing slot may be located at any portion of the framing

cycle so that the frames at both ends of the transmission channel are synchronized at a certain predetermined point. Preferably, however, the frame synchronizing slot is so disposed that the impulse is sent during the time between the last linear scanning element of one frame and the first linear scanning element of a succeeding frame.

The combined picture synchronizing impulses are received in the usual manner, and if transmitted on a carrier wave are amplified by a suitable amplifier. The amplified impulses are then led along two circuits, one of them going to a synchronizing portion of the system and the other going to the picture generating portion of the circuit. While, electrically, both types of impulses are conducted to both circuits indiscriminately, practically they are completely separated so that only synchronizing impulses are effective in the synchronizing portion of the circuit and only picture impulses are effective in the picture portion of the circuit.

The lead going to the synchronizing portion of the system conducts the impulses to the grid 3 of a synchronizing detector SD. This detector is preferably so biased that only impulses having synchronizing amplitudes are detected. The cathode 4 of this detector completes the circuit through ground, and preferably has connected thereto the negative terminals of two sources of potential. These may, if desired, be obtained from the customary power supply of the RF amplifier. Amplified impulses from the detector go from anode 5 through the primaries of two transformers. Transformer 8 is preferably of the air core type, while transformer 9 may have an iron core. The two primaries 10 and 11 of each of these transformers are in series with the anode 5 of the detector and with the positive terminal of a suitable source of current. Primary 11 of transformer has a by-pass condenser 12 of just enough capacity so that the relatively high frequency linear element synchronizing impulses pass therethrough rather than through the primary 11. The secondaries 14 and 15 of the transformers are connected, respectively, to grids 18 and 19 of two grid controlled gaseous discharge tubes. The other ends of the secondaries are connected to a suitable biasing battery 23. The cathodes 20 of these grid controlled gaseous discharge tubes may be energized by a battery 21 and are connected to the bias battery 23 and grounded at 22. Anodes 28 and 29 of the two grid controlled gaseous discharge tubes are connected to junction points 30 and 31, respectively. Junction 30 has a circuit 32 and 33 connected thereto, including a battery 34, rheostat 35 and cathode 36 of a rectifier 37. Junction point 30 is also connected to a condenser 38, the other plate of which is grounded. Junction point 31 is similarly connected through a cathode circuit 40, 41, battery 42, rheostat 43 and cathode 44 of the rectifier 45. This junction is also connected to a grounded condenser 46. Anodes 50 and 51 of the two rectifiers are connected to the positive terminal of a suitable source of potential.

The operation of the synchronizing portion of the system is substantially as follows:

The output of the RF amplifier is suitably detected and fed to the two transformer primaries in series. Frequencies of the order of linear signaling impulses will induce impulses of suitable potential in the secondary 14 and impress these potentials on grid 18. The corresponding impulses through primary 10 will be by-passed

through condenser 12 and have no effect on transformer 9. On the other hand, framing impulses of a substantially lower frequency will pass through transformer primary 10 and 11, condenser 12 being too small to permit such impulses to pass through. Through the action of transformer 9 impulses of suitable potential will be impressed upon grid 19 of the grid controlled gaseous discharge tube.

10 As previously pointed out, grid controlled gaseous discharge tubes have the peculiar property of permitting a gaseous discharge to start upon the slightest change of potential of the grid above a certain critical value. This property of 15 the grid controlled gaseous discharge tubes is availed of by biasing grids 18 and 19 so that any impulses having an amplitude less than synchronizing impulses will fail to exceed the critical potential. Hence, no discharge will be initiated 20 in the grid controlled gaseous discharge tube. In order to obtain a desirable form of the impulse on grids 18 and 19 of the two grid controlled gaseous discharge tubes, secondaries 14 and 15 may be shunted by damping resistances 24 and 25 of a proper value. These resistances may serve to flatten out the synchronizing impulses and insure the operation of the grid controlled gaseous discharge tubes.

Assuming that a synchronizing impulse is impressed upon one of the grids of the grid controlled gaseous discharge tube, this impulse having been amplified to the proper potential, a gaseous discharge between anode and cathode of the grid controlled gaseous discharge tube in question is initiated. Upon this condition, a relatively low impedance path from junction point 30, if the linear synchronizing impulses are considered, to ground, through the grid controlled gaseous discharge tube, is effected. The tendency of any rush of current from anode 50 of 40 rectifier 37 through the grid controlled gaseous discharge tube and to ground will be checked by the rapidly rising drop across rectifier 37. The result will be that the potential of junction point 45 30 and of anode 28 of the controlled gaseous discharge tube will quickly drop to a value too low to support the gaseous discharge through the tube. The gaseous discharge, therefore, will be extinguished.

50 During the period of inactivity of the grid controlled gaseous discharge tube, condenser 38 is charged up through rectifier 37 and the current supply. During the discharge of the grid controlled gaseous discharge tube, condenser 38 is 55 discharged so that charging up of the condenser occurs during the interval between discharges in the grid controlled gaseous discharge tube. By varying the value of resistance 35, the emission from cathode 36 will be varied, with the result 60 that the space current through rectifier 37 will be controlled. Hence, the rate of charge of condenser 38 may be adjusted within certain limits.

In Figure 2 the dotted line curves indicated by LC show the rise of potential across the terminals of condenser 38 or junction point 30 and ground. The lower portion of the synchronizing system operating on the framing impulses works in a similar manner, with the exception that the various constants of the circuit, such as condenser 46 and resistance 43, will have to be 70 changed to operate at the proper frequency. The dotted line across FC indicates the building up of the framing charge in condenser 46. The vertical dotted lines indicate the sudden drop in 75 potential of junction points 30 and 31 occurring

when the grid controlled gaseous discharge tubes have a discharge therethrough. It is preferable to so arrange transformer 8 that framing impulses will also trip the associated grid controlled gaseous discharge tube and start a new linear scanning element. This, however, is not essential, since by making the two transformers responsive to the two frequencies, the timing of the two impulses may be independently adjusted. It is desirable to have the tuning range of the two 10 transformers 8 and 9 wide enough to include the variations in frequency due to variation in number of lines per frame and frames per second customarily encountered. This may be accomplished by close coupling of the windings of each transformer. Hence, only synchronizing impulses either of the linear or framing type result in the rapid drop in potential of junction points 30 and 31, and permit these junction points to steadily 15 rise in potential during intervals between such 20 impulses. It is these changes in potential of the junction points which are utilized in imparting scanning movements at the receiving end.

The output of the RF amplifier is fed to the light generative portion of the system, and, as 25 shown, such impulses go through the primary 60 of a transformer 61 to ground. Shunted across secondary 62 is a tuning condenser 63 and anode 64 of a full wave rectifier 65. Cathode 66 of this rectifier may be energized by any suitable source 30 of current, such as transformer winding 67, and the center thereof is connected through a load resistance 72, back to center 71 of secondary 62. The output of the RF amplifier is, therefore, rectified and results in differences of potential across 35 load resistance 72.

These impulses, which contain both the synchronizing and picture impulses, are translated into light impulses of corresponding intensity. This translating means may take on any form 40 whatsoever and, as shown here, is a variation of the well-known Braun cathode ray tube. Such tube has an electron emitting cathode, one or more anodes which function to attract electrons from the cathode, the geometry of the tube 45 structure being such that the electrons, by virtue of their speed, by-pass the anodes and bombard a suitable screen. This screen, as is well-known in the art, emits a phosphorescent glow, the intensity of which depends on the electron speed as 50 well as the electron density.

The cathode ray tube here shown and indicated by numeral 76, has a cathode 75 and a plurality of electrodes 85 and 86. Electrode 80 may consist of a cup-shaped member having an aperture 55 81, through which the electron stream from cathode 75 is adapted to pass. Electrode 80 functions as a control electrode and is connected by lead 82 back to point 71 on secondary 62. Cathode 75, which may be energized by transformer winding 77, is connected by lead 73 to cathode 66 of the full-wave rectifier 65. The result is that variations of potential across load resistance 72, representing rectified picture and 60 synchronizing impulses, are impressed on electrode 80 and cathode 75. This change in bias of electrode 80 functions in a manner similar to a grid in a vacuum tube to control the intensity 65 of the electron beam.

Electrode 85, which is shown here as a cup-shaped member whose open end is away from the cathode, is connected to a suitable source of potential, here shown as a point on a resistance 126, across the terminals of which a suitable direct potential is maintained. Electrode 86, which may 75

be a flat member, has impressed thereon a still higher positive potential. Electrodes 85 and 86 are both provided with suitable apertures, which register with the aperture 81 of electrode 80. All 5 these electrodes are disposed in longitudinal alignment with the axis of the tube.

The electron stream, after having passed through the apertures 80, 85 and 86, has been accelerated so that the electrons are traveling at a 10 sufficiently high speed for creating light flashes on screen 95. In order to impart scanning movements to the light flashes, the direction of the electron stream is varied. This is done in a well-known manner, by having two sets of scanning 15 condensers 92 and 93, the planes of which are at right angles to each other, disposed along the axis of the tube so that the electron stream tends to pass between the plates of the condensers. It will be noted that one of the plates of each of 20 condensers 92 and 93 is connected so that both are at the same potential as electrode 86, which, as previously pointed out, is maintained at a constant positive potential. Junction points 30 and 31 are respectively connected to the other plate 25 of scanning condenser 93 and 92 by leads 130 and 131. Inasmuch as the potentials of these two junction points with respect to ground vary, as pointed out before, it is clear that the effective potential across the scanning condensers 92 and 30 93 varies in accordance with the synchronizing impulses.

Synchronizing impulses at the control electrode of tube 76 will not be translated into light impulses since they represent darkness.

35 While any source of unvarying potential may be used to bias tube 76, I preferably use the one disclosed here, since it results in the generation of high voltages at the tube without the necessity for handling such high voltages at more than a few places. Such a power supply consists of a transformer having a primary 100, energized in any suitable manner, and a secondary 101 connected between two leads 102 and 103. Lead 103 is connected to anode 104 of a half-wave rectifier 109 and cathode 106 of another half-wave rectifier 107. Cathode 106 may be energized in any suitable manner, as by a transformer 108. Cathode 105 of rectifier 109 may be energized by transformer winding 111 and is connected to a 45 lead 112, grounded at 113. Anode 118 of rectifier 107 is connected to a lead 119, which is connected to a cathode 120 of a current limiting tube. Cathode 120 may be suitably energized by a source 121. Lead 102 is connected through 50 condensers 117 and 124, respectively, to leads 112 and 119. Anode 122 of the current limiting tube is connected to a lead 123 to cathode 75 of the cathode ray tube 76. From lead 123 across to lead 112 a resistance 126 is disposed, which functions to smooth out the rectified output, as well as provide a convenient voltage divider to a point of which electrode 85, as previously pointed out, is connected. Electrode 86 and one of the plates of each of scanning condensers 92 and 93 are all 55 connected to a lead 114, which is connected to lead 112.

In the normal operation of the rectifying system, each cycle from secondary 101 of the transformer will serve to charge one of the two condensers 117 and 124, and at the same time go 60 through one of the rectifiers 107 or 109. The discharge of one of condensers 117 or 124 added to the current going through one of the two rectifiers, functions to practically double the voltage 65 across the secondary of the transformer. Inas-

much as the current required to operate the two is quite minute, the resistance suffices, in ordinary practice, to filter out the output.

In order to operate the receiving system, the only adjustments necessary, under normal conditions, are at rheostats 35 and 43. These adjustments serve to vary the charging rates to condensers 38 and 46, respectively. This is equivalent to changing the slope of the dotted lines in Figure 2 indicated by letters LC and FC and 10 serves to vary the dimension of the image. In order to obtain synchronization with the transmitting station, it is only necessary to adjust both rheostats until the image is of normal proportions. In order to obtain comic effects as 15 the result of the distortion of the image in one direction relative to another direction, it is possible to adjust one of rheostats 35 or 43 away from its normal position. This results in increasing or decreasing the charging rate of one 20 condenser and results in the beam within tube 76 scanning in one direction at a faster or slower rate compared to the other direction. It may be desirable to vary the potential of electrode 85 25 to control beam focus.

We claim:

1. In a television receiver adapted to have impressed thereon two series of synchronizing impulses, scanning means comprising two transformers, the primaries thereof being in series 30 with each other, means for rendering one of said transformers responsive to both series of synchronizing impulses, means for rendering the other transformer responsive to only one series of synchronizing impulses, damping means associated with each of said transformer secondaries and means including a grid controlled gaseous discharge device associated with each of said transformer secondaries for utilizing said synchronizing impulses for scanning purposes. 35

2. A television receiver adapted to operate with two series of synchronizing impulses having different times of duration, light generating means for transforming electrical image impulses into light, and scanning means therefor comprising 45 two separate circuits, means for rendering one of said circuits responsive to both series of synchronizing impulses, means for rendering the other circuit responsive to only one series of synchronizing impulses, local means associated with 50 each of said circuits whereby the potential in each said circuit rises at a predetermined rate only during the interval between successive synchronizing impulses of the same series, and means conductively isolated from said aforementioned 55 local means and including a gaseous discharge device for effecting a sudden drop in said potential.

3. In a television receiving system the combination of a circuit having electrical picture 60 impulses on a carrier frequency therein, means for amplifying the carrier frequency impulses to the full degree of amplification, a full wave rectifier connected with the output of the amplifying means and supplied with energy therefrom, 65 a load circuit connected with the output of said rectifier and light generating means directly connected across said load for transforming said electrical picture impulses into light impulses.

4. The system of claim 3 in which said light 70 generating means comprises a cathode ray tube.

5. In a television receiving system, a receiving channel, a pair of channels branching off therefrom, one of said channels being adapted to exercise a scanning control, the other of said channels 75

being adapted to exercise a light intensity control, said scanning channel including the following, a pair of hot cathode grid-controlled gas discharge devices, means for impressing synchronizing impulses on each of said grid controls to permit a discharge to take place, a condenser associated with each of said gas discharge devices, means for charging said condensers at a predetermined rate during the periods when said discharge devices are non-conducting, said discharge devices and condensers being so connected that said condensers can discharge through said gas devices when said devices are conducting, a cathode ray tube having a pair of electrostatic scanning controls, connections from each of said condensers to each of said scanning controls whereby the potential of said condensers is communicated to said scanning control, said light control channel having impressed thereon both image and synchronizing impulses and comprising means for rectifying said combined impulses, and said rectifying means being conductively isolated from said receiving channel, but conductively connected to the cathode and control electrode of said cathode ray tube for transforming said signal impulses into correspondingly varying electron streams.

6. In a television receiver, a receiving channel, said receiving channel branching off into two channels, one of said channels comprising a scanning control channel and including means for selecting synchronizing impulses from combined image and synchronizing impulses, a grid-controlled gaseous discharge device, means for transmitting said selected synchronizing impulses to the control electrode of said gaseous discharge device, said control electrode circuit being damped, a condenser connected across the cathode and anode of said gas discharge device, means including a source of potential and a vacuum tube for charging said condenser at a predetermined rate, said gas discharge device being adapted to have a discharge initiated therein upon the existence of a synchronizing impulse on said control electrode and to discharge said condenser during this period, a cathode ray tube having an electrostatic control condenser, a connection between one plate of said control condenser and a plate of said first-mentioned condenser, whereby the potential of said control condenser varies with said first-mentioned condenser, said other channel comprising a two-element rectifying device and connections to said cathode ray tube whereby the output of said rectifier controls the electron stream of said cathode ray tube, and a high tension power supply for said cathode ray tube for biasing said scanning control condenser comprising a pair of half-wave rectifiers connected in series with each other and with a pair of series-connected condensers, a source of alternating potential bridged between said two rectifiers and said two condensers, and connections from said power supply to said cathode ray tube for biasing said control condenser.

7. In a television system, the method of signalling which comprises scanning a picture subject along a series of lines to develop for each line of scanning picture signalling impulses varying in amplitude between a minimum and a maximum value determinable by the intensity of light and shadow on the subject, producing synchronizing signalling impulses following in time relationship each series of picture signalling impulses for each line of scanning, reversing the polarity of the synchronizing impulses to produce a signal in the direction of the minimum picture signal and of a

greater amplitude in the direction of minimum picture signal than any produced picture signal, and adding together the two produced series of signals to produce a composite series of signals representing both the picture subject and the synchronizing impulses. 5

8. In a television system, the method of signalling which comprises scanning a picture subject along a series of lines to develop for each line of scanning picture signalling impulses varying in amplitude between a minimum and a maximum value determinable by the intensity of light and shadow on the subject, separately producing synchronizing signalling impulses following in time relationship each series of picture, signalling impulses for each line of scanning, reversing the polarity of the synchronizing impulses to produce a signal in the direction of the minimum picture signal and of a greater amplitude in the direction of minimum picture signal than any produced picture signal, and adding together the two produced series of signals to produce a composite series of signals representing both the picture subject and the synchronizing impulses. 10 15 20

9. In a television system, the method of signalling which comprises scanning a picture subject along a series of lines to develop for each line of scanning picture signalling impulses varying in amplitude between a minimum and a maximum value determinable by the intensity of light and shadow on the subject, producing synchronizing signalling impulses following in time relationship each series of picture signalling impulses for each line of scanning, electrically reversing the polarity of the synchronizing impulses to produce a signal in the direction of the minimum picture signal and of a greater amplitude in the direction of minimum picture signal than any produced picture signal, and adding together the two produced series of signals to produce a composite series of signals representing both the picture subject and the synchronizing impulses. 25 30 35 40

10. In a television system, the method of signalling which comprises scanning a picture subject along a series of lines to develop for each line of scanning picture signalling impulses varying in amplitude between a minimum and a maximum value determinable by the intensity of light and shadow on the subject, producing synchronizing signalling impulses of different duration for line and frame synchronizing following in time relationship each series of picture signalling impulses for each line of scanning, reversing the polarity of the synchronizing impulses to produce a signal in the direction of the minimum picture signal and of a greater amplitude in the direction of minimum picture signal than any produced picture signal, and adding together the two produced series of signals to produce a composite series of signals representing both the picture subject and the synchronizing impulses. 45 50 55 60

11. In a television system, the method of signalling which comprises scanning a picture subject along a series of lines to develop for each line of scanning picture signalling impulses varying in amplitude between a minimum and a maximum value determinable by the intensity of light and shadow on the subject, producing synchronizing signalling impulses of different duration for line and frame synchronizing following in time relationship each series of picture signalling impulses for each line of scanning, electrically reversing the polarity of the synchronizing impulses to produce a signal in the direction of the minimum picture signal and of a greater amplitude 65 70 75

in the direction of minimum picture signal than any produced picture signal, and adding together the two produced series of signals to produce a composite series of signals representing both the picture subject and the synchronizing impulses.

12. In a television system, the method of signalling which comprises scanning a picture subject along a series of lines to develop for each line of scanning picture signalling impulses varying in amplitude between a minimum and maximum value determinable by the intensity of light and shade of the subject, independently producing signalling impulses following in time relationship each series of picture signalling impulses for each line of scanning, amplifying said independently developed impulses to the exclusion of the picture signal impulses, adding the picture signal impulses to said latter produced signalling impulses in such a manner that the polarity of said latter produced signalling impulses is such as to produce a signal in the direction of the minimum picture signal and of a greater amplitude in the direction of minimum signal than any produced picture signal, and producing from said added signals a composite series of signals representing both the picture subject and synchronizing impulses.

13. In a television system, the method of signalling which comprises scanning a picture subject along a series of lines to develop for each line of scanning picture signalling impulses varying in amplitude between a minimum and maximum value determinable by the intensity of light and shade of the subject, independently producing signalling impulses of a predetermined duration following in time relationship each series of picture signalling impulses for each line of scanning and of a different predetermined duration following the complete series of picture lines, amplifying said independently produced impulses to the exclusion of the picture signals, adding the picture signal impulses to said independently produced signalling impulses in such a manner

that the polarity of said independently produced signalling impulses is such as to produce a signal in the direction of the minimum picture signal and of a greater amplitude in the direction of minimum signal than any produced picture signal, and producing from said added signals a composite series of signals representing both the picture subject and synchronizing impulses for both line and frame synchronizing control.

14. In a television receiving system, a receiving channel, a pair of channels branching off therefrom, one of said channels being adapted to exercise a scanning control, the other of said channels being adapted to exercise a light intensity control, said scanning channel including the following, a pair of hot cathode grid-controlled gas discharge devices, means for impressing synchronizing impulses on each of said grid controls to permit a discharge to take place, a condenser associated with each of said gas discharge devices, means for charging said condensers at a predetermined rate during the period when said discharge devices are non-conducting, said discharge devices and condensers being so connected that said condensers can discharge through said gas devices when said devices are conducting, a cathode ray tube having a pair of cathode ray deflecting means, connections from each of said condensers to each of said deflecting means whereby the potential of said condensers is communicated to said scanning means, said light control channel having impressed thereon both image and synchronizing impulses and comprising means for rectifying said combined impulses, and said rectifying means being conductively isolated from said receiving channel, but conductively connected to the cathode and control electrode of said cathode ray tube for transforming said signal impulses into correspondingly varying electron streams.
